CLAIM

The ornamental design for a control box vibrator device, as shown and described.

DESCRIPTION

FIG. 1 is a front view of a battery controller box for a vibrator device, showing my new design.

FIG. 2 is a back view thereof, rotated 180 degrees from that shown in FIG. 1;

FIG. 3 is a left side view of the battery controller box for a vibrator device.

FIG. 4 is an opposing right side view thereof, rotated 180 degrees from that shown in FIG. 3.

FIG. 5 is a top view of the battery controller box for a vibrator device; and,

FIG. 6 is a bottom view thereof, rotated 180 degrees from that shown in FIG. 5.

The broken lines shown in the drawings are included for the purpose of illustrating environmental structure and form no part of the claimed design.
